UNITED STATES PATENT OFFICE

ALBERT HAPPEL, OF TOLEDO, OHIO, ASSIGNOR, BY MESNE ASSIGNMENTS, TO GIFFORD-WOOD COMPANY, OF HUDSON, NEW YORK, A CORPORATION OF NEW YORK

ICE-SCORING MACHINE

Application filed November 8, 1926. Serial No. 147,003.

The invention relates to ice scoring machines of that type designed for the scoring of large ice cakes so that they may be readily severed into smaller sections of predetermined size and weight.

In the present state of the art it is usual to score the large cakes both longitudinally and transversely and upon opposite sides of the cake. It is also usual to arrange the scoring saws on pairs of arbors which are upon opposite sides of the ice cake. This complicates the construction of the machine as it is necessary to drive all of the various arbors as well as to provide for relative movement between the arbors and the ice cake in transverse directions.

It is the primary object of the present invention to simplify the construction by dispensing with one of the arbors holding the series of saws for transverse scoring. This is accomplished by a construction in which a single arbor provided with a series of saws is used for scoring the ice cake successively upon opposite sides thereof. A further object of the invention is to effect the relative movement between the ice cake and saws with a simple construction of mechanism thereby greatly reducing the cost of manufacture. With these and other minor objects in view the invention consists in the construction as hereinafter set forth.

In the drawings;

Figure 1 is a side elevation partly in vertical longitudinal section.

Figure 2 is a front elevation.

Figure 3 is a rear elevation.

Figure 4 is a vertical cross section.

Figure 5 is a side elevation showing the longitudinal feeding means for the ice cakes.

Figure 6 is an enlarged side elevation showing the means for supporting the ice cake on the conveyor bar.

Figure 7 is a cross section through the longitudinal conveyor.

Figure 8 is a section on line 8-8 of Figure 6.

Figure 9 is a diagrammatic sectional plan view.

As specifically shown my improved machine comprises a pair of A-shaped end

frames A and A' which are connected to each other by a series of longitudinally extending frame bars B. At the base and extending beneath this frame is a platform C on to which the ice cake may be fed longitudinally through the opening in one of the A frames. D and D' are the saws for longitudinally and centrally scoring the ice cake on opposite sides thereof which saws are mounted upon arbors E and E' journaled in bearings on the frame A to be in advance of the point of entrance of the ice cake. Thus, the cake when fed on to the platform C within the frame will be longitudinally scored.

At a point above the path of the ice cake and near the apex of the frames A, A', there is arranged to extend longitudinally and centrally an arbor F bearing a series of saws G, G' etc. for effecting the transverse scoring. The ice cake is brought into operative relation to these saws by first moving it laterally from the centre of the frame to one side thereof, then elevating it along guides parallel to this side of the frame so as to pass the saws and to score one side of the cake, then moving the cake transversely to the opposite side of the frame and lowering it past the saws to score the opposite side thereof, such movement being accomplished as follows.

H is a swinging frame comprising a pair of arms H', H² arranged adjacent to the opposite end frames A, A' and pivotally attached thereto at the points H³. The lower ends of these arms are connected by a shaft H⁴ on which is pivotally mounted a pad or frame H⁵ for bearing against one side of the ice cake. As shown in Figure 2 the frame and pad are initially at the right and the pad is held in vertical position by bearing with its lower end against the stops H⁶ on frames A, A'. In this position the pad will be cleared by the ice cake when fed longitudinally into the frame upon the platform C.

At a certain point in the cycle of operation the frame H is swung to the left, Figure 3, this being accomplished by cams I upon a longitudinally extending shaft K journaled in bearings in the frame. This swinging movement will push the ice cake off from the platform C and up an inclined platform C' sub-

stantially perpendicular with the side of the A-frame and into a position for being elevated along this side of the frame. During this swinging movement the pad H³, being 5 pivotally mounted on the shaft H⁴, is free to change in angle to correspond to the changed angularity of the block.

The elevation of the block is accomplished by a feed bar J extending longitudinally of 10 the frame and carried by chains J' and J² at opposite ends of said frame. These chains travel over sprocket wheels K, K', K² arranged respectively at the apex of the A frames and upon the right and left hand sides 15 at the base thereof. Thus, when motion is communicated to these chains the bar J will be moved up on the left hand side of the frame carrying the ice cake up with it and after passing around the sprockets K will descend 20 on the opposite side of the A frame lowering the ice cake therewith. It is however necessary to provide means for holding the ice cake while the bar J passes over the sprocket K and for transferring the cake from the left 25 hand side to the right hand side of the frame. Such a means is formed by the basket or receptacle L which is of a width corresponding to the ice cake and is open at its bottom to receive said cake. This receptacle is pivot- 30 ally mounted on a shaft L' journaled in bearings on upward extensions A³ of the frames A, A'. There is also provided mechanism for swinging this basket from a position in alignment with the left hand side of the frame to 35 a position in alignment with the right hand side thereof. This swinging movement is timed with the movement of the bar J so that when said bar has passed over the sprockets K the ice cake will be in a position to descend 40 with said bar past the scoring saws G.

For accomplishing the various movements that have been described I have provided operating mechanism preferably of the following construction. M is a motor mounted on 45 a bracket frame M' attached to the frame A. M² is a sprocket on the motor shaft which drives a chain M³ passing about sprockets M⁴, M⁵, M⁶ arranged respectively adjacent to the apex of the A frame and upon the left and 50 right hand sides thereof. The sprockets M⁵ and M⁶ are connected by beveled gears M⁷ to the arbors E and E' for the longitudinal scoring saws D and D'. The sprocket M⁴ is mounted upon the arbor F and forms the 55 driving means therefor. Thus all of the scoring saws are simultaneously driven and at the same speed.

At the opposite end of the arbor F adjacent to the frame A' there is arranged a step down 60 gearing N between said arbor and a shaft K³ on which the sprockets K are mounted. By means of this gearing the chains J' are simultaneously driven at a greatly reduced speed from that of the arbors. Upon the 65 shaft K³ is a sprocket O connected by a chain

O' with a sprocket O² which drives a step down gearing O³ for actuating the shaft I' so that the said shaft is driven at a still further reduced speed. The timing of these parts is such that for one revolution of the 70 shaft I' the chains J' and feed bar J also complete one full revolution.

The swinging of the basket L from its position for receiving the ice cake to the position for discharging the same is preferably effected by the following mechanism. P is a bell crank lever fulcrumed at P' on the upward extension A³ of the frame A. One arm P² of this lever extends into the path of the feed bar J preferably engaging a roller 80 P³ on said bar. The other arm P⁴ of the bell crank lever is connected by a link P⁵ to a pivot P⁶ on the basket L at one side of the shaft L'. The parts are so proportioned that after the roller P³ contacts with the arm P² the further movement of the rod J over the sprocket will swing the bell crank P and through the link P⁴ will rock or tilt the basket 85 L. This will move said basket from a position for receiving the ice block to a position 90 for discharging the same during the time interval in which the rod J is passing over the sprocket.

For intermittently feeding the ice cakes 95 into the machine and past the scoring saws D, D' any suitable mechanism may be employed. I preferably use for this purpose a mechanism which forms the subject matter of Patent No. 1,631,125 and which therefore will not be described herein in detail. Briefly this mechanism includes a reciprocating feeder bar V having a dog V' for engaging the rear end of the ice cake pivotally attached to said feeder bar and adapted to collapse or fold downward during the rearward 100 movement of said bar so as to slide under the ice cake in front of the machine. The mechanism for actuating the bar V includes a feed chain W beneath the platform which in turn is driven through a sprocket and chain connection W' and through beveled gears W² from a shaft W³ connected to the sprocket wheel K². Further description of this mechanism will be unnecessary.

Cakes of artificial ice are usually of tapering form so as to be readily removable from the freezing cans but in longitudinally scoring the ice cakes it is desirable to form a kerf in the median plane or non parallel to the sides of the cake. To accomplish this I preferably place upon the feed bar J a supporting member Q for the small end of the cake. See 110 Figs. 1 and 6. This member, as shown, is provided with an annular knife edge Q' for biting into the ice and holding the cake from 115 relative longitudinal movement. The member Q is also preferably adjustable upon the shaft by means of set collars Q² secured on opposite sides thereof by set screws Q³. This permits of so adjusting the member Q that it 120 130

will support the small end of the ice cake at the proper height to score said cake along its median line.

Complete operation of the machine

5 In the complete operation of the machine the ice cakes are first placed on the platform in the path of the reciprocating feeder V which on its forward stroke advances the cake 10 through the opening in the frame and in engagement with the longitudinal scoring saws D and D'. The cake is guided during such advancement by guides V² on the platform so that it will be directed into the machine adjacent to the pad H⁵. The amount of movement is slightly greater than required so that in the subsequent transverse movement, the cake must be drawn rearward to properly align it with the transverse scoring saws. This is effected by an inclined spring 15 bumper X at the forward end of the cake which presses it rearward against a guide X' during the transverse movement under the actuation of the pad H⁵.

25 When the cake is moved transversely to the left, Figure 2, its outer face will come into engagement with a spring guide Y which will press it toward the guide bars Y' parallel with the A frames. This spring guide also 30 holds the cake to the guides while it is being elevated and during the scoring operation. At the completion of the upward movement the cake is engaged with the basket L which is then actuated by the roller P³ bell crank 35 lever P⁴ to be rocked on its shaft L'. The rocking movement is sufficient to carry the cake into alignment with the guides on the opposite side of the frame and while this occurs the feed bar J, which has elevated the 40 cake, moves over the sprocket K and begins its descent on the opposite side of the frame. The cake being supported solely by this bar J will be lowered with it passing the scoring saws G which score the opposite side of the 45 cake in the planes of the scorings on the first side. Finally when the cake reaches the bottom of the frame, it will rest upon the inclined platform Z upon which it slides to one side.

In order that the sections of the ice cake 50 between the scores may be of approximately equal weight, the preferred machine has means to definitely locate the ice cake longitudinally with respect to the scoring saws. This is primarily accomplished by the member Q having a knife edge Q' which as previously described, bites into the bottom of the 55 cake and holds the same from longitudinal displacement relative to the bar J. This bar J is also held from displacement preferably 60 by providing at opposite ends thereof bearings J³ (Figs. 6 and 8) which slidably engage with guide surfaces on the frames A, A'.

Obviously, the present invention is not restricted to the particular embodiment thereof herein shown and described. Moreover, it

is not indispensable that all the features of the invention be used conjointly, since they may be employed advantageously in various combinations and sub-combinations.

What I claim as my invention is:

1. In an ice scoring machine the combination with a scoring saw, of means for moving an ice cake relative thereto to successively present opposite faces of said cake in operative relation to opposite sides of said saw to be scored thereby. 70

2. In an ice scoring machine, the combination with an arbor, and a plurality of scoring saws mounted thereon, of means for moving an ice cake relative to said arbor and saws to successively score opposite faces of said cake by opposite sides of the saw. 80

3. In an ice scoring machine, the combination with an arbor and a series of scoring saws mounted thereon, of means for feeding an ice cake past said saws successively on opposite sides thereof and in opposite directions to score both sides with the same saws. 85

4. In an ice scoring machine, the combination with an arbor and a series of scoring saws mounted thereon, of means for elevating an ice cake on one side of said saws to score one face of said cake and for lowering said cake on the opposite side of said saws to score the opposite face of the cake. 90

5. In an ice scoring machine, the combination with an arbor and a series of scoring saws mounted thereon, of means for feeding an ice cake longitudinally beneath said arbor and saws to clear the same, means for scoring the ice cake longitudinally while thus fed beneath said arbor, means for elevating the ice cake on one side of said arbor and saws to transversely score one face of said cake, and means for lowering said cake on the opposite side of said arbor and saws to transversely score the opposite face of said cake. 100

6. In an ice scoring machine the combination with an arbor and a series of scoring saws mounted thereon, of a frame for supporting said arbor and saws providing clearance beneath the same for the feeding of an ice cake longitudinally, means for scoring said ice cake while thus fed beneath said arbor, means for raising and lowering said ice cake respectively on opposite sides of said arbor and saws, means for feeding the ice cake laterally from its position beneath said arbor into a position for operative engagement with the raising means whereby one 115

face of the cake is transversely scored by said saws, and means at the upper end of said frame for transferring said ice cake into operative relation with the lowering means whereby the opposite face of said cake is 120 transversely scored by the same saws.

7. In an ice scoring machine, the combination with an arbor and a series of scoring saws mounted thereon, of means for feeding an ice cake longitudinally in a direction 130

parallel to said arbor and into transverse alignment therewith, means for scoring said cake longitudinally while thus fed, and means for feeding said ice cake transversely past said arbor successively on opposite sides of the saws and in opposite directions to transversely score said cake on its opposite sides.

8. In an ice scoring machine, the combination with an arbor and a series of scoring saws mounted thereon, of means for feeding an ice cake longitudinally in a direction parallel to said arbor and below the same, means for scoring the ice cake longitudinally while thus fed, an endless carrier surrounding said arbor and ice cake, means for moving the ice cake laterally into engagement with said carrier, and guides for holding opposite sides of the cake in operative relation to said scoring saws during its movement past the same in the ascent and descent of said carrier.

9. In an ice scoring machine, the combination with an arbor and a series of scoring saws mounted thereon, of an endless carrier passing through an orbit surrounding said arbor, means for engaging an ice cake with said carrier on the ascending side thereof whereby one face of said cake is fed by and in operative relation to said scoring saws, and means operating upon said cake while at the upper end of said carrier to bring the reverse side of said cake in operative relation to said scoring saws during the descent of the carrier.

10. In an ice scoring machine, the combination with an arbor and a series of scoring saws mounted thereon, of an endless carrier having a substantially triangular orbit surrounding said arbor, said arbor being arranged near the upper end of the triangle, means for feeding an ice cake longitudinally beneath said arbor and within said triangle, an oscillatory carrier for moving said cake laterally into engagement with the ascending side of said carrier, guides for holding said cake in operative relation to opposite sides of said scoring saws respectively during the ascent and descent of said carrier, and means for shifting said cake laterally at the upper end of said carrier to bring the opposite face of said cake in engagement with the saws during the descent of said carrier.

11. In an ice scoring machine, the combination with an arbor and a series of scoring saws mounted thereon, of endless carrier chains movable through similar triangular orbits surrounding said arbor at opposite ends of the series of scoring saws, a carrier bar extending between said carrier chains, means for feeding an ice cake longitudinally into the triangular area below said arbor, an oscillatory carrier for shifting said cake laterally into the path of said carrier bar on

the ascending side of the carrier chains, guides for directing the cake in operative relation to said saws and on opposite sides thereof respectively in the ascent and descent of the carrier, and a shifter at the upper end of said carrier for moving said cake laterally to bring the opposite side thereof in engagement with said saws during the descent of the carrier.

12. In an ice scoring machine, the combination with an arbor and a series of scoring saws mounted thereon, of an endless carrier travelling through a substantially triangular orbit surrounding said arbor with the latter arranged adjacent to the apex of the triangle, means for feeding an ice cake longitudinally into the area of said triangle below said arbor, an oscillatory member for moving said ice cake laterally into engagement with the ascending side of said carrier, and a second oscillatory member for moving said ice cake laterally in the opposite direction when at the upper end of said triangular orbit, whereby opposite sides of said ice cake are passed in operative relation to opposite sides of said scoring saws respectively in the ascent and descent of said carrier.

13. In an ice scoring machine, the combination with an arbor and a series of scoring saws mounted thereon, of a substantially triangular open frame having journal bearings for said arbor adjacent to the apex thereof, carrier chains travelling through similar triangular orbits at opposite ends of said series of saws, a feed bar mounted on and extending between said chains, means for feeding an ice cake longitudinally into said triangular frame beneath said arbor, an oscillatory member on said frame for moving said ice cake laterally into the path of said feed bar when on the ascending side of said carrier chains, guides for directing said ice cake in operative relation to opposite sides of said scoring saws respectively during the ascent and descent of said feed bar, and means for shifting said cake laterally when said feed bar is passing the upper end of said triangular orbit to bring the opposite face of said cake adjacent said saws during the descent of the carrier.

14. An ice scoring machine comprising, in combination, a substantially triangular open frame, an arbor journaled in bearings near the upper end of said frame, a series of scoring saws mounted on said arbor, endless carrier chains mounted on said frame to travel through similar triangular orbits at opposite ends of said series of saws, a feed bar secured to and extending between said carrier chains, a platform at the bottom of the triangular space within said frame, means for feeding an ice cake longitudinally into said frame and upon said platform, an oscillatory member for moving said ice cake laterally on said platform and into the path of said feed bar

on the ascending side of said carrier chains, guides for holding said cake in operative relation to said scoring saws on opposite sides thereof respectively during the ascent and descent of said feed bar, and an oscillatory member at the upper end of said frame for moving said cake laterally on said feed bar to bring the opposite face of said cake in operative relation to said saws during the descent of the carrier.

15. An ice scoring machine comprising, in combination, a substantially triangular open frame, a platform at the bottom of the open area within said frame, means for feeding an ice cake longitudinally within said frame upon said platform, means mounted on said frame for scoring the cake longitudinally during such movement, endless feed chains travelling through similar triangular orbits at opposite ends of said series of saws and spaced from each other by more than the length of the ice cake, a feed bar mounted upon and extending between said chains, an oscillatory frame within said triangular frame, a pad pivotally attached to said oscillatory frame for bearing against one face of said ice cake to move the same during the oscillation of said frame into the path of said feed bar on the ascending side of said chains, guides for said ice cake to direct the same in operative relation to said scoring saws on opposite sides thereof respectively during the ascending and descending of said feed bar, and an oscillatory member at the upper end of said frame for shifting said ice cake laterally in the opposite direction from said first mentioned oscillatory member.

16. In an ice scoring machine the combination with an arbor and a series of scoring saws mounted thereon, of endless carrier chains movable through similar triangular orbits surrounding said arbor at opposite ends of the series of scoring saws and spaced from each other by more than the length of the ice cake, a carrier bar extending between said carrier chains, means for feeding an ice cake longitudinally into the area below said arbor, an oscillatory member for shifting said cake laterally into the path of said carrier bar from the ascending side of the carrier chains, a guide engaging an end of the cake during its lateral movement for positioning the same in predetermined longitudinal relation to said series of scoring saws, and means on said carrier bar for preventing longitudinal displacement of said cake while carried thereby, whereby said cake will be scored in the same transverse planes on opposite sides respectively in the ascent and descent of said carrier.

17. In an ice scoring machine, the combination with an arbor and a series of scoring saws mounted thereon, of an endless carrier chain movable through similar triangular orbits surrounding said arbor at opposite

ends of the series of scoring saws and spaced from each other by more than the length of the ice cake, a carrier bar extending between said carrier chains, means for feeding a tapering ice cake into the path of said carrier bar and in predetermined longitudinal relation with said series of scoring saws, and an edged member projecting from said bar to engage the smaller end of said tapering cake to hold the median line of said cake parallel with said bar and to prevent longitudinal displacement of the cake while in engagement therewith.

18. An ice scoring machine comprising, in combination, a series of scoring saws mounted on a power-driven arbor; an endless power-driven conveyor for carrying an ice cake around two sides of said saws; a bar extending transversely of and attached to said conveyor for engagement with one face of the ice cake; and a knife-edged member on the bar near one end, the knife edge biting into the ice cake and tending to prevent longitudinal displacement thereof relative to the bar and being so spaced relative to the bar that the cake is held spaced from the bar at the corresponding end, so that the median line of the cake is substantially parallel with said bar.

19. An ice scoring machine for use with commercial tapered ice cakes, comprising, in combination, a series of power-driven scoring saws mounted on the same shaft; an endless, power-driven conveyor for carrying an ice cake around two sides of said saws to be scored thereby; and means secured to the conveyor for elevating the smaller end of a cake relative to its support on the conveyor so that the median line of the cake is substantially at right angles to the planes of said saws.

20. An ice scoring machine comprising, in combination, a frame; an arbor; a series of scoring saws mounted on the arbor; an endless conveyor for raising and lowering an ice cake respectively on opposite sides of said arbor and saws; and means at the upper end of said frame for transferring said ice cake from the elevating flight of the endless conveyor into operative relation with the lowering flight of the endless conveyor, whereby two opposite faces of the cake are scored by the same saws.

In testimony whereof I affix my signature.

ALBERT HAPPEL 120
